UNITED STATES PATENT OFFICE.

RUFUS W. APPLEGARTH AND EVERETT D. MOORE, OF BALTIMORE,
MARYLAND.

WATER COIL BOILER.

SPECIFICATION forming part of Letters Patent No. 409,134, dated August 13, 1889.

Application filed May 11, 1889. Serial No. 310,399. (No model.)

To all whom it may concern:

Be it known that we, RUFUS W. APPLEGARTH and EVERETT D. MOORE, citizens of the United States, residing at Baltimore, in the State of Maryland, have invented new and useful Improvements in Water Coil Boilers, of which the following is a specification.

Our invention has for its object to provide a simple, economical, and thoroughly efficient means for steaming, washing, flushing, and cooling the pipes of a beverage-drawing apparatus without the use of chemicals.

The pipes that are employed for conducting beer, wine, or other liquids from a keg, barrel, or other source of supply to the tap or faucet of a beverage-drawing apparatus are extremely liable to become fouled and internally coated with sediment from the liquors or beverages passed through them. The impurities thus deposited in the pipes are often injurious to health, besides tainting and rendering impalatable such liquids as may be subsequently drawn. By forcing solutions of potash, lime, and other chemicals through the pipes they may be cleansed to some extent; but such substances are themselves liable to form injurious compounds that are not easily removed from the pipes.

It is the purpose of our invention to avoid the use of chemicals, and provide a means for thoroughly cleansing the pipes of a beverage-drawing apparatus by the use of steam and hot and cold water, as hereinafter set forth.

To this end our invention consists in the apparatus hereinafter described and claimed, and which is illustrated in the annexed drawings, in which—

Figure 1 is a sectional elevation of our improved steam-generator and pipe-cleansing apparatus. Fig. 2 is a plan of the same with its cover removed. Fig. 3 is a view of the under side of the top plate of a burner for heating the steam-generator.

Referring to the drawings, the numeral 1 designates a stand provided with legs 2, and having a central opening in which is supported an atmospheric or Bunsen gas-burner 3, to the lower end of which a gas-supply tube 4 is or may be attached. In the lower part of the gas-burner 3 are a number of air-

inlets 5 for the admission of atmospheric air to become mixed with the gas supplied to the burner. The upper part of the burner 3 is flared outwardly, as shown in Fig. 1, to form 55 a circular bottom plate 6, having an upwardly-flanged rim 7, on which a circular top plate 8 is supported. The top plate 8 is of greater diameter than the bottom plate 6, and is secured thereto by screws 9 or otherwise. The 60 under side of the top plate 8 is beveled at the periphery and provided with an annular series of radiating grooves 10 for exit of the mixture of gas and air from the space between the burner-plates. On the under side 65 of the top plate 8, at suitable intervals between the grooves 10, as shown in Fig. 3, may be located lugs 11 to engage the inner side of the flanged rim 7, for the purpose of properly centering the top plate. 70

On the stand 1, within an annular flange 12 formed thereon, is supported a cylindrical shell or casing 13, having a series of lateral air-inlets 14 near its lower end. If desired, an air-inlet 15 may be provided in the stand 1, 75 on which the shell 13 is supported.

Within the shell or casing 13 is a water-heating and steam-generating coil 16, having the form of a frustum of a cone, arranged with its larger end downward and near the 80 lower end of the casing. This coil is securely supported in the shell or casing by means of its inlet and outlet pipes, which perforate said casing near its upper end.

The upper or inlet leg *a* of the coil 16 is 85 extended upward to connect, by means of a bend or elbow 17, with a horizontal water-inlet pipe 18 of comparatively large bore, through which water may be introduced to flood the coil when desired. This inlet-pipe 90 18 is provided outside the shell or casing 13 with a hand-valve 19 for controlling the supply of water. Communicating with the main water-inlet pipe 18, on opposite sides of the valve 19, as shown in Fig. 2, is a by-pass tube 95 20, of smaller diameter, and provided with a petty valve 21, which is to be opened and the large valve 19 closed when it is desired to admit into the coil 16 only a small stream or spray of water for the purpose of rapidly 100 generating steam in said coil, which should be previously heated. The same result can

be obtained by providing the main water-inlet pipe with a valve having two passages of different diameters—one for a large stream of water, when it is desired to flood the coil, and 5 the other for a small stream of spray, when the coil is to be used for generating steam.

The lower or outlet leg 6 of the coil 16 is preferably extended upward along the inside of the shell 13, and connects with a bend or 10 elbow 22, which in turn connects with an outlet-pipe 23, that is passed horizontally through the shell.

Water may be supplied to the inlet-pipe 18 through a hose or flexible tubing 24, that can 15 connect with a house-service pipe or other convenient water-supply, and steam and water may be delivered from the outlet-pipe 23 through a hose or flexible tubing 25, adapted to be connected at one end to said outlet-pipe 20 and at the other end with the pipes to be cleansed and flushed.

It will be seen that the lower portion of the coil 16 surrounds the flaring Bunsen burner 3 in such a manner as to receive the full effect 25 of the radiating jets of non-luminous but intensely-heating flame issuing from the radiating-grooves or gas-exits 10 of the atmospheric gas-burner. The coil 16 may be thus quickly heated before admitting water thereto, 30 and then by opening the valve 21 a small stream or spray of water can be introduced through the by-pass 20 into the heated coil 16, where it will be quickly converted into steam, and can be conducted through the 35 hose 25 into and through the pipes of a beverage-drawing apparatus. The steam that is thus passed through the pipes to be cleansed will soften and loosen the slime, scale, and sediment accumulated therein, so that such 40 impure and injurious deposits will readily become detached and be forced out at the opened tap or faucet. The sediment or scum being thus softened and somewhat removed by means of the stream passed into and 45 through the fouled pipes of the beverage-drawing apparatus, the valve 19 of the main water-inlet pipe 18 should now be opened so as to admit sufficient water to flood the heated coil 16, in which the water will become quickly 50 heated, and, passing on to the beverage-pipes, will force out any scale or sediment that may not have been removed by the steam. The supply of gas to the burner 3 should now be cut off, so as to extinguish the flame, and a 55 continuous stream of cold water may now be passed through the coil 16 and into the connected pipes of the beverage-drawing apparatus to cool the same and remove every vestige of sediment.

60 By providing the main water-inlet pipe 18 with a hand-valve 19 and a by-pass 20, of smaller diameter, and having a valve 21, as described, whereby one valve admits only sufficient water to generate steam, while the

other or larger valve must be opened to supply sufficient water to flood the coil, a simple and convenient means is provided for properly operating the apparatus, without requiring the services of a skilled engineer.

The lower part of the coil 16 is provided with 70 a draw-off cock 26 for draining the coil after it has been in use.

As shown, the shield or casing 13 is provided with a conical top or removable cover 27, having a chimney 28 for exit of the products of combustion.

In order to retain the heat of the apparatus and render it more economical, the casing 13 may have a lining 29, of asbestos or other fire-proof material, and a layer or plate 30, 80 of similar material, may be placed above the water-heating and steam-generating coil.

While especially designed for use in cleansing the pipes of a beverage-drawing apparatus without requiring the employment of 85 lime, potash, soda, or other objectionable substances, it is obvious that this apparatus may also be usefully and conveniently employed as a portable steam-generator and water-heater for bath-tubs, vapor-baths, and other 90 purposes.

What we claim as our invention is—

1. The combination of a shell or casing having air-inlets near the bottom, a water-heating and steam-generating coil supported 95 in said casing, and a valved inlet-pipe communicating with the upper end of said coil and adapted to admit thereto either a large or small stream of water, the lower leg of said coil being extended upward within the casing and adapted at its upper end for attachment of a flexible hose, substantially as described.

2. The combination of a shell or casing having air-inlets near the bottom, a Bunsen 105 burner located in the lower part of said shell, a water-heating and steam-generating coil supported in the shell or casing with its lower portion in position to be acted on by the diverging flame-jets of the Bunsen burner, a 110 valved inlet-pipe communicating with the upper end of the coil for the purpose of introducing water to flood the same, said inlet-pipe provided with a by-pass having a petty valve to control the introduction of a small 115 stream of water into the coil for the purpose of generating steam therein, a draw-off cock located in the lower part of the coil, and an outlet-pipe extending from the lower end of the coil, substantially as described.

In testimony whereof we have affixed our signatures in presence of two witnesses.
